US0D1052199S

(12) **United States Design Patent** (10) Patent No.: **US D1,052,199 S**
(45) Date of Patent: ** Nov. 19, 2024

(54) **RECEIVER FOR ELECTRIC FENCE SYSTEM**

(71) Applicant: **Shenzhen Wellturn Technology Co., Ltd.**, Shenzhen (CN)

(72) Inventor: **Xingsheng Luo**, Shenzhen (CN)

(57) **CLAIM**

The ornamental design for a receiver for electric fence system, as shown and described.

DESCRIPTION

FIG. 1 is a front, left and bottom perspective view of a receiver for electric fence system, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the receiver for electric fence system that form no part of the claimed design.
